UNITED STATES PATENT OFFICE.

MILTON M. ADLER, OF NEWARK, NEW JERSEY.

PYROTECHNICAL DEVICE.

Application filed October 27, 1922. Serial No. 597,409.

To all whom it may concern:

Be it known that I, MILTON M. ADLER, a citizen of the United States, residing at Newark, in the county of Essex and State 5 of New Jersey, have invented certain new and useful Improvements in Pyrotechnical Devices; and I do hereby declare the following to be a full, clear, and exact description of the invention, such as will enable others 10 skilled in the art to which it appertains to make and use the same, reference being had to the accompanying drawings, and to characters of reference marked thereon, which form a part of this specification.

15 This invention relates, generally, to improvements in pyrotechnical devices; and the invention has reference, more particularly, to an improved detonating fire-work or fire-cracker.

20 The invention has for its principal object to provide a novel construction of detonating fire-work or fire-cracker which is safe to handle, which will not fly apart when set off so as to endanger the eyes or person of 25 the user, or entail the risk of igniting fires, and which is constructed to produce, when set off, a series or intermittent succession of detonations, rendering the same of pleasing and interesting effect, and providing a 30 fire-work or fire-cracker which will operate for a comparatively long time after it is ignited.

Other objects of this invention, not at this time more particularly enumerated, will be 35 clearly understood from the following detailed description of the same.

With the various objects of this invention in view, the same consists, primarily, in the novel detonating fire-work or fire-cracker 40 hereinafter set forth; and, the invention consists, furthermore, in the novel arrangements and combinations of the several devices and parts, as well as in the details of the construction of the same, all of which 45 will be hereinafter more fully described in the following specification, and then finally embodied in the claims appended hereto.

The invention is clearly illustrated in the accompanying drawings, in which:—

50 Figure 1 is a perspective view of the complete fire-work or fire-cracker, made according to and embodying the principles of the present invention; Figure 2 is a longitudinal central section through the same; Figure 3 is a cross section through the same, taken 55 on line 3—3 in said Figure 2; and Figure 4

is a plan view of a combustible carrier sheet upon which a plurality of pastilles or lozenges of pyrotechnical composition are mounted, and which is adapted to be enclosed in the outer case of the fire-work, said view also showing the attachment to said carrier sheet of an ignition fuse.

Similar characters of reference are employed in all of the hereinabove described views, to indicate corresponding parts.

Referring now to said drawings, the reference character 1 indicates a combustible carrier sheet preferably made of thin paper, such as tissue paper, upon which are caused 70 to adhere a plurality of pastilles or lozenges 2 consisting of a pyrotechnical composition adapted to produce detonations when ignited. It will, of course, be understood that there are many different pyrotechnical compositions known to those skilled in the art which, when ignited, will produce detonations, and consequently, in this respect I do not desire to limit myself to the use of any particular composition so characterized, although I prefer to employ a composition 75 heretofore known and used to produce intermittent detonations, and which comprises a mixture of gum-arabic, carbonate of magnesium, white phosphorus, red ochre and potassium chlorate. The pastilles or lozenges 2 of pyrotechnical composition are arranged in a group the members of which are suitably spaced apart. It is preferable to treat the paper or other carrier sheet 1 with some 80 chemical adapted to insure continued combustion thereof once the same is ignited. A chemical such as saltpeter may be employed for such purpose, although I do not wish to be understood as confining myself to the use 85 of that substance for the purpose indicated.

After the carrier sheet 1 with its pastilles or lozenges of pyrotechnical composition applied thereto is prepared, a fuse element 3, of a suitable easily combustible material, is 90 attached to the carrier sheet. One end of said fuse element is attached by a suitable adhesive to the carrier sheet, preferably (although not necessarily) to the center of the sheet where the group of pastilles or lozenges 95 2 of pyrotechnical composition is mounted. After said fuse element 3 is thus attached thereto, the carrier sheet is folded or crumpled into a roughly ball-like body from the interior of which projects the free end 100 110 of said fuse element 3.

The reference character 4 indicates a cy-

cylindrical or tubular casing, open at its respective ends, and preferably made of comparatively heavy paper or light cardboard. The ball-like body into which the carrier sheet is formed (as above explained) is thrust into the interior of said tubular casing 4, so that the same is positioned intermediate the open ends of the latter, and so that the free end of said fuse-element 5 may project exteriorly from one open end of the casing easily accessible for ignition. The casing 4 with the carrier sheet thus enclosed therein, is provided with an outer cover or jacket 5, preferably made of paper. 10 This cover or jacket 5 consists (in preferred form) of a strip of paper having a width exceeding the length of the tubular casing 4. This strip is wound spirally about the exterior surface of said tubular casing, so that the marginal portions thereof project beyond each end of said tubular casing. The projecting portions thus formed are thereupon tucked into the respective open ends of the tubular casing as at 6, to not 20 only interlock the cover or jacket to the tubular casing but to thereby provide by such tucked-in portions 6 internal annular stops or shoulders for retaining the carrier sheet against accidental displacement or ejection 30 from its operative disposition within the interior of said tubular casing. The lengths of said tucked-in portions 6 are such as to not entirely close the ends of the tubular casing, so that ventilating openings 7 are 35 provided at each end of said casing for the admission of air into the interior of the same, to thus supply sufficient oxygen to assure complete and continued combustion of the carrier sheet and its pastilles or lozenges 40 of pyrotechnical composition once the same is ignited.

The carrier sheet 1 and its pastilles or lozenges 2 of pyrotechnical composition being enclosed within the tubular casing 4 in the manner above described, the device is ready for use. In operation, the free exteriorly projecting end of the fuse element 3 is ignited, whereby the combustion thereof causes an igniting spark or flame to travel 45 into the interior of the casing 4 and thereupon ignite the combustible carrier sheet 1 to in turn ignite or set off the pastilles or lozenges 2, so that the latter will upon ignition produce a succession of intermittent 50 explosions or detonations, which will continue for a comparatively long time. The detonating material being enclosed in the casing 4, which is sufficiently resistant not to disrupt under the force of the explosions 55 thereof, is retained against flying about as the carrier sheet and pyrotechnical material is disrupted, and the hollow interior of the casing tends to emphasize the reports or sounds of the detonations. It will thus be 60 apparent that the device is unusually safe 65

for children's amusement since there is little danger of scattering particles of fire or smoldering fragments burning the child, igniting its clothing, or objects in the vicinity wherein the device is set off. Furthermore, owing to the spaced arrangement or separation of the members of the group of pastilles or lozenges of pyrotechnical composition on the carrier sheet, the ignition of the same is sure to be intermittent so that a succession of detonations similar to that produced by igniting a whole pack of old-fashioned fire-crackers is produced. The effect of a succession of intermittent detonations is increased when the particular composition above referred to is employed for the pastilles or lozenges, since it is characteristic of such composition that it burns slowly and produces intermittent detonations while burning, so that in addition to the separate reports of the different individual pastilles or lozenges upon ignition thereof, each such individual pastille or lozenge will of itself produce a plurality of intermittent reports. 75 80 85 90 95

I am aware that some changes may be made in the arrangements and combinations of the parts making up the device, as well as in the details of the construction and composition of said parts, without departing from the scope of this invention as above set forth, and as defined in the following claims. Hence, I do not limit myself to the exact arrangements and combinations of the various parts as described in the above specification, nor do I confine myself to the exact details of the construction of said parts as illustrated in the accompanying drawings. 100 105

I claim:

1. A pyrotechnical device, comprising a tubular casing within which is disposed a combustible carrier means treated with a pyrotechnical composition adapted to detonate when ignited, and a fuse element attached by one end to said carrier means with its free end projecting outwardly from an open end of said casing. 110 115

2. A pyrotechnical device, comprising a tubular casing within which is disposed a combustible carrier means treated with a pyrotechnical composition adapted to detonate when ignited, a fuse element attached by one end to said carrier means with its free end projecting outwardly from an open end of said casing, a cover member encircling said casing, and the marginal portions of said cover member being tucked into the open ends of said casing to serve as internal annular stops against accidental displacement of said carrier means from said casing. 120 125

3. A pyrotechnical device, comprising a tubular casing within which is disposed a combustible carrier means, said carrier 130

means having attached thereto, a plurality of pastilles formed of a pyrotechnical composition adapted to detonate when ignited, and a fuse element attached by one end to 5 said carrier means with its free end projecting outwardly from an open end of said casing.

4. A pyrotechnical device, comprising a tubular casing within which is disposed a 10 combustible carrier means, said carrier means having attached thereto a plurality of pastilles formed of a pyrotechnical composition adapted to detonate when ignited, a fuse element attached by one end to 15 said carrier means with its free end projecting outwardly from an open end of said casing, a cover member encircling said casing, and the marginal end portions of said cover member being tucked into the open 20 ends of said casing to serve as internal annular stops against accidental displacement of said carrier means from said casing.

5. A pyrotechnical device, comprising a tubular casing, a combustible carrier sheet 25 having a plurality of spaced apart bodies of pyrotechnical composition attached thereto adapted to detonate when ignited, a fuse element attached by one end to said carrier sheet, said carrier sheet being formed with 30 a ball-like body with said fuse element projecting therefrom, and said carrier sheet thus formed being enclosed within said tubular casing so that the free end of said fuse element projects outwardly from an open 35 end of said casing.

6. A pyrotechnical device, comprising a tubular casing, a combustible carrier sheet having a plurality of spaced apart bodies of pyrotechnical composition attached thereto 40 adapted to detonate when ignited, a fuse

element attached by one end to said carrier sheet, said carrier sheet being formed into a ball-like body with said fuse element projecting therefrom, and said carrier sheet thus formed being enclosed within said tubular 45 casing so that the free end of said fuse element projects outwardly from an open end of said casing, a cover member encircling said casing, and the marginal end portions of said cover member being tucked 50 into the open ends of said casing to serve as internal annular stops against accidental displacement of said carrier means from said casing.

7. A pyrotechnical device, comprising an 55 outer casing, a combustible carrier means treated with a pyrotechnical composition adapted to detonate when ignited, a fuse element attached by one end to said carrier means, said carrier means being wadded into 60 said outer casing with the free end of said fuse element projecting exteriorly from said casing.

8. A pyrotechnical device, comprising an 65 outer casing, a combustible sheet, a plurality of pastilles of a detonating pyrotechnical composition attached to said sheet in spaced apart relation one to another, a fuse element attached by one end to said sheet, said sheet being wadded into said outer casing with 70 the free end of said fuse element projecting exteriorly from said casing.

In testimony that I claim the invention set forth above I have hereunto set my hand this 14th day of October, 1922.

MILTON M. ADLER.
